UNITED STATES PATENT OFFICE

112,981

DESIGN FOR A CABINET FOR A PIANO OR SIMILAR ARTICLE

Arthur C. Ansley, New York, N. Y.

Application September 9, 1938, Serial No. 79,811

Term of patent 7 years

To all whom it may concern:

Be it known that I, Arthur C. Ansley, a citizen of the United States, residing at New York, in the county of New York and State of New York, have invented a new, original, and ornamental Design for a Cabinet for a Piano or Similar Article, of which the following is a specification, reference being had to the accompanying drawing, forming part thereof.

The figure is a perspective view of a cabinet for a piano or similar article, showing my new design.

I claim:

The ornamental design for a cabinet for a piano or similar article, as shown.

ARTHUR C. ANSLEY.
